KEY HOLDING DEVICE

Ruth M. Bryan, Tulsa, Okla.

Application January 25, 1937, Serial No. 122,285

5 Claims. (Cl. 70—457)

This invention relates to a key holding device designed primarily to be coupled to a door knob and attached to a key when in holding position, but it is to be understood that the device may 5 be coupled with the key attached thereto to any suitable support or hanger therefor arranged in juxtaposition to the lock with which the key is associated, and the invention has for its object to provide, in a manner as hereinafter set forth, 10 a key holding device to prevent the loss of the key when the latter is detached or drops from a lock and further for holding the key, when detached or dropped from the lock in close proximity to the latter.

15 A further object of the invention is to provide, in a manner as hereinafter set forth, a device of the class referred to which is of especial benefit in relation to the keys of the locks on inner doors of buildings as it will act to prevent the 20 loss of the keys, as well as function to prevent children from removing the keys and losing them.

25 Further objects of the invention are to provide, in a manner as hereinafter set forth, a device for the purpose referred to which is simple in its construction and arrangement, strong, durable, compact, readily installed with respect to a door knob, support or hanger and the key, thoroughly efficient in its use, over- 30 coming the inconveniences of lost or misplaced keys, permanently retaining the key in a position to be used when the latter is detached or dropped from a lock, not unsightly in appearance or cumbersome, and inexpensive to manu- 35 facture.

To the above ends essentially and to others which may hereinafter appear, the invention consists of the novel construction, combination and arrangement of parts as will be more specifically referred to and are as illustrated in the accompanying drawing wherein is shown an embodiment of the invention, but it is to be understood that changes, variations and modifications 40 may be resorted to which fall within the scope 45 of the invention as claimed.

In the drawing:

Figure 1 is a fragmentary view in front elevation of a door showing the adaptation of the holding device, in front elevation with respect to 50 the stem of a door knob mounted on the latch shaft, the stem of a key inserted into the door lock and with said stems and shaft shown in transverse cross section.

Figure 2 is a fragmentary view in side elevation of a door showing the adaptation of the

key holding device with respect to the door knob and the door key suspended.

Figure 3 is a side elevation of the device extended, and

Figure 4 is a fragmentary view in perspective 5 showing the form of body part and closure employed for the coupling member and holding element.

Referring to the drawing, a door is indicated at 4, the lock for the key at 5, the latch operating shaft at 6, a door knob at 7, the stem of the knob at 8 and which is fixed to one end of shaft 6, the key-hole opening at 9, the door key at 10, the stem or shank of the key at 11, and the skeleton head of the key at 12. The 15 stem or shank 11 merges into the inner side of the head 12 at the transverse center of the latter. The foregoing elements are of known construction.

The key holding device in accordance with 20 this invention includes a pair of flexible extension members 13, 14, an annular attaching element 15, an annular coupling member 16 common to said members 13, 14 and element 15 and an annular key holding element 17. 25

The members 13, 14 may be of chain-like form and are so shown. The members 13, 14 are of any suitable length, but preferably the member 13 is of greater length than member 14. The inner ends of the members 13, 14 are connected, 30 as at 18, 19 respectively to opposite sides of the outer periphery of the coupling member 16 adjacent to one side of the horizontal diametric median of the latter. Preferably the members 13, 14 will have their inner ends welded to coupling member 16 and are so shown. The outer end of the member 13 is connected, as at 20 to the outer periphery of the inner side of the attaching element 15 at the horizontal diametric median of the latter. Preferably the outer end 40 of member 13 will be welded to attaching element 15 and it is so shown. The outer end of flexible member 14 is connected, as at 21 to the outer periphery of the inner side of holding element 17 at the horizontal diametric median 45 of the latter. Preferably the outer end of member 14 will be welded to holding element 17 and it is so shown.

Preferably the coupling member 16 and holding element 17 are of the same diameter and are so 50 shown. The attaching element 15 is of less diameter than that of member 16 and element 17. The element 15 is in the form of a ring. The coupling member 16 and attaching element 15 are of like construction but are oppositely disposed with 55

respect to each other and each consists of a split circular hollow body part 22 and a spring controlled slidable closure 23 for the space between the ends of said body part 22. The closure 23 is of arcuate contour, is mounted in body part 22 and is of a length and so arranged to extend from one to within the other end of body part 22 for closing the aforesaid space. The closure 23 is formed adjacent one end with an outward lug 24 to facilitate the opening movement of the closure and for limiting closing movement of the latter. The lug 24 operates through a slot 25 provided in body part 22 adjacent the end 26 of the latter. The outer end wall of slot 25 coacts 15 with the lug 24 for limiting the closing movement of the closure 23.

When the device is installed the member 13 is extended around the stem of the knob and the element 15 attached to the member 16 whereby 20 the device is coupled to the knob. The holding element 17 is positioned relatively to the shank or stem of the key in a manner whereby the latter will extend through the element 17 and the device is then coupled to the key. If the latter is 25 removed or dropped from the lock the key will be held by element 17 and suspended in proximity to the lock.

What I claim is:

1. In a key holding device, a pair of oppositely 30 disposed flexible extension members, a normally closed annular coupling member having spring controlled means for opening and closing it, said member being arranged between and having its sides rigidly secured to the inner ends of the extension members, a permanently closed annular attaching element for connection to the coupling member and having its inner side rigidly secured to the outer end of one of the extension members, and a normally closed annular holding 35 member having spring controlled means for opening and closing it, said holding element having its inner side rigidly secured to the outer end of the other of said extension members.

2. In a key holding device, a pair of oppositely 40 disposed flexible extension members, a normally closed annular coupling member having spring controlled means for opening and closing it, said member being arranged between and secured to the inner ends of the extension members, a permanently closed annular attaching element for connection to the coupling member and having its side secured to the outer end of one of the extension members, and a normally closed annular holding member having spring controlled means 45 for opening and closing it, said holding element having its inner side secured to the outer end of the other of said extension members, said coupling member and holding element being of like form and oppositely disposed with respect to each 50 other.

3. In a key holding device, a pair of oppositely 55 disposed flexible extension members, a normally

closed annular coupling member having spring controlled means for opening and closing it, said member being arranged between and having its sides rigidly secured to the inner ends of the extension members, a permanently closed annular attaching element for connection to the coupling member and having its inner side rigidly secured to the outer end of one of the extension members, a normally closed annular holding member having spring controlled means for opening and closing it, said holding element having its inner side rigidly secured to the outer end of the other of said extension members, said coupling member being secured to said extension members adjacent one side of the horizontal diametric center 10 thereof, and said extension members being secured to said elements at the horizontal diametric centers of said elements.

4. In a key holding device, a pair of oppositely 15 disposed flexible extension members, a normally closed annular coupling member having spring controlled means for opening and closing it, said member being arranged between and secured to the inner ends of the extension members, an annular attaching element for connection to the coupling member and secured to the outer end of one of the extension members, a normally closed annular holding member having spring controlled means for opening and closing it, said holding element being secured to the outer end 20 of the other of said extension members, said coupling member being secured to said extension members adjacent one side of the horizontal diametric center thereof, said extension members being secured to said elements at the horizontal 25 diametric centers of said elements, said attaching element being of less diameter than that of the coupling member and holding element, and said coupling member and holding element being of like diameter.

5. In a key holding device, a pair of oppositely 30 disposed flexible extension members, one of greater length than the other, a permanently closed annular attaching element permanently secured to the outer end of the extension member of greatest length, a normally closed annular holding element permanently secured to the outer end of the other of said extension members, a normally closed annular coupling member arranged between and permanently secured at opposite sides thereof to the inner ends of said extension members, and said attaching element for detachable connection to said coupling member to provide said extension member of greatest length in the form of a loop for connecting the 35 device to the stem of a door knob, said coupling member having a slidable part to provide for connecting the attaching element therein, and said holding element having a slidable part to provide for detachably connecting the stem of a door key 40 thereto.

RUTH M. BRYAN.
